UNITED STATES PATENT OFFICE.

WILLIAM B. CAPPER, OF DAVIS, WEST VIRGINIA.

RACK FOR ROLLED GOODS.

Application filed December 7, 1925. Serial No. 73,810.

The present invention relates to racks for roll goods, for example linoleum and seeks to combine in an article of this character a novel dispensing structure.

5 Previous racks of this character have had the disadvantage of occupying too much store space, and where a compact structure is employed, this is generally accompanied by complicated parts and mechanism.

10 In order to measure off a length of linoleum it is necessary to have a sturdy support for the supply roll in connection with means enabling the goods to be unrolled by a simple force.

15 Furthermore, the dispensing roll must be capable of easy positioning and not be in the nature of an obstacle to prevent full use of the rack as a display cabinet, or occupy space otherwise needed for store purposes.

20 The invention aims to secure these various advantages by providing a sliding relation between the main rack and the auxiliary frame carrying the dispensing roll.

This is advantageous for commercial use, 25 and the novel construction is moreover desirable to the trade because a display rack and dispensing roll arrangement has been worked out embodying so few parts that it can be made with very little cost.

30 The rack is easily positioned about a store or other place, and the goods are removable and replaceable with ease.

In the drawings:

Figure 1 is a top plane view of the invention.

35 Figure 2 is a side elevation.

Figure 3 is an end view on the line 2—2 of Figure 2.

40 Figure 4 is a sectional view through one of the supporting hubs for the linoleum rolls.

In the drawings I have shown my improved rack as a whole at 10. Construction may be of wood or other suitable material capable of withstanding wear and having 45 a neat finish.

The base is composed of parallel boards 11 and 12, and the upper portion is formed of similar coinciding members 13 and 14.

The members comprising the base and upper portion are spaced apart a suitable dis-

tance as shown at 15 and 16 for a purpose which will presently appear.

Base members 11 and 12 in their spaced relation may be screwed to the floor or otherwise secured, although this is not necessary. 55 The upper members 13 and 14 are secured together in their spaced relation by cross bars 17, screwed or otherwise secured to the upper surfaces of the members. These bars 17 are preferably arranged one at each 60 end of the rack and one on each side of the middle of the rack.

Formed in the base members 11 and 12 are circular recesses 18 adapted to receive upwardly projecting cylindrical pins or 65 hubs 19. Arranged on the hub 19 in each case and bearing on the base is a ball bearing device 20, and disposed for rotary movement on the ball bearing device is a spool head or flange 21 fitting the hub 19. The 70 upper portion of the rack is provided with holes 22 to receive headed detachable pins 23 which are shown in normal position depending below the members 13 and 14.

The pins 19 and 23 are suitably spaced 75 longitudinally of the several members and are arranged with their axes coinciding.

Thus, to insert a supply roll of goods 24 in the rack, it is only necessary to place one end of the bore of the roll upon the lower 80 pin 19, displace the pin 23 a suitable degree and bring the upper end of the bore in position to receive the projecting end of pin 23 which is then allowed to drop into the bore. The roll is easily removable by a similar movement of the several parts.

It is to be noted that the roll is rotatably mounted in the rack since it bears upon the spool head 19 which is revoluble upon the ball bearing device, and thus goods may 90 easily be unrolled.

The rack may be more firmly held in position by disposing above it a fixed support, and in the case of a store, this is effectively carried out by arranging a shelf for other 95 goods over the rack. To such shelf, the rack is attached by means of braces 25 suitably secured to the cross bars 17. This arrangement enables the rack to be positioned in a shelf portion of the store along a wall 100

if this is necessary and the rack is equally satisfactory due to the positioning of the goods cut from the piece in the usual manner.

Arranged to one side of the rack and interengaging therewith is an auxiliary frame indicated as a whole at 26.

This frame comprises upper and lower members or bars 27 and 28 respectively, of an exact size to easily and slidably fit within the spaces 15 and 16 between the respective rack members 11 and 12, and 13 and 14.

Each member 27, 28, is enlarged adjacent one end as shown at 29, and the members are connected at this end by a post or vertical standard 30. This post at its upper end is extended as at 31, for a purpose to be presently set forth.

Disposed on the lower member 28 is a pin 32 and ball bearing 33, and fitting on the said pin and bearing is a roller 34. At its other end, the roller is keyed to a vertical shaft 35 extending thru the enlarged portion 29 of the upper bar. A sufficient amount of play exists between the key slot of the roller and the shaft therein and the upper end of the roller and the bar 28 to allow the roller to be raised a sufficient distance over the pin 32, so it may be removed and replaced as desired.

30 The spool head 36 of the roller bears upon the ball bearing so that the roller is easily revolvable. Spaced intermediate its ends, the roller may be provided with spring clips 37 to engage and hold the end of a piece of goods.

The roller is operated to receive goods as unwound from a supply roll by means of suitable gearing. A gear housing 38 is mounted on the post 30 and the gearing is operated by a crank or handle connected to one of the gear shafts therein. This will operate a vertical shaft 39 supported on the standard by a bracket 40, and shaft 39 has a gear 41 meshing with a horizontal gear 42 on a shaft 43, mounted in the extension 31 of the post 30. This shaft at its opposite end has a gear 43 meshing with a gear 44 on the vertical shaft 35 which is keyed to roller 34.

50 In the drawings, I have shown the auxiliary frame in extended position for winding a desired quantity of goods from the main rack. When the rack is not in use, the auxiliary frame, by means of the bars 27, 28, sliding in the spaces 15 and 16 respectively, can be telescoped with the main rack and a minimum of store space is thus occupied.

When it is desired to measure off a quantity of material from one of the supply rolls, the auxiliary frame is pulled out a suitable distance and the free end of the material is engaged with the roller 34. The crank or handle is then turned to operate the roller 34 and draw off a desired amount 65 of material from the supply roll onto the

measuring or dispensing roller and the goods cut from the piece in the usual manner.

Where a short length of material is being dispensed, the material may be pulled from the winding roller 34 or the crank may be reversed to unwind the material from the said roller. In the case of large quantities, this plan may be resorted to or the roller with the material may be removed from the auxiliary frame and the material easily slipped therefrom in rolled form.

Thereafter, the auxiliary frame may be slid back into normal position out of the way.

The size of the rack and frame may be varied as desired, the rack preferably being of a height to accommodate the greater widths of linoleum and the pins being of a size to readily engage in the bore of the supply roll.

I have shown the main rack as holding two parallel equally spaced series of rolls, and it is to be observed that in any one of the positions of the supply roll, the invention is equally effective. It is only necessary to feed the free end of the material to the dispensing roller with the frame in extended position, and the roller can be readily operated.

The construction is simple and sturdy and provides for a nice display of the goods as well as combining the feature of a slidably mounted dispensing roller.

Various modifications of the idea may be worked out, all of which I consider within the purview of my invention.

What I claim as new is:

1. A device of the character described, comprising a supply rack for carrying a plurality of rolls of material to be dispensed, said rack having a base and an upper portion each composed of spaced parallel members, the members of the upper portion being secured together, and a frame slidable in the spaces between the respective upper and lower members and carrying a roller and actuating means therefor for winding material dispensed from said first mentioned rolls.

2. A device of the character described, comprising a supply rack for carrying a plurality of rolls of material to be dispensed, and a frame carrying a roller and actuating means therefor for winding material dispensed from said supply rolls, said frame being slidable toward and from the supply rack in a plane parallel therewith.

3. A device of the character described, comprising a supply rack carrying a plurality of rolls of material to be dispensed, and a frame carrying a roller and actuating means therefor for winding material dispensed from said supply rolls, said frame being slidable within the supply rack and

toward and from the same in a plane parallel therewith.

4. A device of the character described comprising a supply rack, said supply rack being formed of upper and lower members each having a guideway, supply rolls mounted between said upper and lower members, a second rack carrying a dispensing roller and operating means therefor, said second

rack having extensions adapted to slide in 10 said guideways of the supply rack, whereby the second rack may be moved toward and from the supply rack in a plane parallel therewith.

In testimony whereof I have hereunto set 15 my hand.

WILLIAM B. CAPPER.
